SAFETY DEVICE FOR GRINDERS

Application filed March 2, 1929. Serial No. 343,878.

My invention relates to internal grinding machines with particular reference to an automatic safety device.

A purpose of my invention is to prevent the wheel unit portions of the individual grinder units of a multiple unit internal grinder from moving to normal grinding position if the conditions are not right for grinding, either by reason of the wheel having finally worn away to a predetermined limit of safety or by reason of a work piece having been inserted imperfectly into the work-holder portion of the unit.

A further purpose is to latch the grinding wheel portion of any grinder unit of a multiple spindle grinder away from its normal grinding position by an engagement between an imperfectly inserted work piece and latch operating mechanism having preferably either electric or mechanical connection with the latch.

A further purpose is to latch the grinding wheel portion of any grinder unit of a multiple spindle grinder away from its normal grinding position by the engagement between normally spaced members supported respectively upon the wheel unit and its slideway carrier, and operating preferably either electrically or mechanically to hold the unit from its normal grinding position.

Further purposes will appear in the specification and in the claims.

I have elected to show two only of the many different forms in which my invention may be embodied, selecting forms that are efficient in operation, inexpensive to manufacture and which will illustrate the principles of my invention.

Figure 1 is a broken and somewhat diagrammatic top plan view of a multiple spindle internal grinder having applied to it one form of my invention.

Figure 2 is a vertical section of Figure 1.

Figure 3 is an enlarged vertical section showing the same grinder machine as is seen in Figure 2 but having applied to it a different form of my invention.

Like numerals refer to like parts in all figures.

Describing in illustration and not in limitation and referring to the figures:—

I have illustrated my invention embodied on one of the forms of multiple grinder shown in my copending application No. 126, 55 403 entitled "Grinder" filed August 2, 1926. The invention is applicable to multiple grinders of widely different types, but showing it embodied with a form of grinder disclosed and described in detail in said application makes it less necessary to go into detailed description of structure that is in itself not part of the present invention. The invention is well adapted for use with any one of the forms shown in said application, 60 65 and to many other forms of grinders not there shown.

Multiple grinding machine

The grinding machine is intended to operate upon duplicate work pieces which are continuously fed to grinder units of the machine as they pass a loading point and are discharged from the same units after having been ground to finished size as the units pass an unloading point preparatory to again reaching the loading point.

The machine comprises a plurality of grinding units spaced around a turn-table that is mounted upon suitable stationary 75 supporting structure. The grinding operations at each unit begin when the unit receives a work piece as it passes the charging or loading point and finally end at the unit with the removal of the finished work piece from the unit while the unit is passing the unloading point.

Each grinder unit comprises a work-holder unit adapted to rotate during the travel of the turn-table and a wheel unit adapted to present a rapidly revolving and vertically traversing grinding wheel to the work throughout the grinding portion of the orbit.

A common feed cam mounted upon the 95 stationary supporting structure causes the traversing wheels to travel successively around the same orbit. The wheels initially enter the work interiors out of contact with the work surfaces and feed progressively 100

into the work until the piece has been cut to a predetermined finish size. This occurs at some point before the unloading station has been reached. There the wheel units 5 successively rise to be out of the way for the unloading and subsequent loading operations. They remain raised until they reach a point somewhat beyond the loading point in the direction of travel, and then again 10 move down for traverse grinding.

My safety device is adapted to operate upon the individual units while passing a point of their common orbit that is located beyond the loading point but not so far 15 beyond it as is the point at which traverse grinding begins.

In the illustration the turn-table 5 is pivoted upon a stationary central post 6 of stationary supporting structure 7 and is rotated by a suitable motor 8 mounted upon the base of the central post and geared at 20 9 to rotate the turn-table.

The work-holders 10 may be of any suitable type and are shown continuously rotated 25 by individual motors 11 mounted upon downwardly extending portions 12 of the turn-table and geared at 13 to the respective holders.

Each wheel unit 14 is supported in a horizontal guideway 15 that extends outwardly 30 from a carrier 16 with which it is rigidly connected and the individual carriers 16 are adapted to vertical reciprocation along vertical traverse guideway standards 17 of 35 the turn-table.

The grinding unit carrier 16 is positioned and traverse motion of the wheel is effected by cooperating engagement between a suitable stationary upwardly directed undulatory cam 18 surrounding the central axis 40 of the turn-table and rods 19. These rods extend downwardly from inwardly extending lugs 20 of the carriers 16, through suitable perforations 21 in the lower portion of 45 the turn-table to rest upon the cam surface 18.

The wheel units are fed to the work by a cooperating engagement between a common cam 22 mounted upon the stationary supporting structure, and the outer ends of the 50 feed rods 23 adjustably threaded into the individual wheel units.

Each wheel unit is spring-pressed outwardly along its guideway at 24 to continuous engagement at the outer end of its feed rod with the cam.

The feed rods are provided with star wheels 25 rigidly fastened to them, for screw adjustment, automatic or hand, of the effective lengths of the rods, and thereby of the positions of the wheel units along their guideways.

As the wheel wears away, by reason of grinding and diamonding, the feed arms 23 65 must be gradually lengthened to maintain

the grinding surface in proper alignment for grinding to exact size. This lengthening is conveniently effected automatically by a feed engagement between the teeth of the star wheels 25 and one or more projecting pin or pins 26 on the supporting structure, the wheel being desirably diamonded after such feed to insure exactly proper alignment of the grinding element.

All of the foregoing has been described in greater detail in my prior application.

The present invention is directed at a safety device adapted to operate upon the individual units while passing between the positions for feeding in new work pieces and that for the initial entry of the wheels for traverse grinding. In the plan view Figure 1 the work pieces are fed into the successive holders at a suitable platform 27 and traverse grinding normally begins at some point 28 that is some little distance beyond the position for feeding in the new work pieces.

The improper condition for grinding may result from an imperfect insertion of a work piece or from a grinding wheel having become worn away to a predetermined limit at which it is considered unadapted to effective grinding.

In either case my device prevents the wheel unit from moving down into the position that it normally occupies during traverse grinding. Preparatory to delivery of the work pieces which may take place at a platform 29 placed suitably back of the loading platform, the wheel carrier is raised into position to lift the wheel out of the way above the work-holders and it normally remains in its raised position until some time after a new work piece has been inserted and until the point 28 is reached.

I mount a movable arm 30 across the common path of the upwardly projecting ends 31 of the work pieces in a position that is somewhat before the point 29 at which the wheel carrier normally starts down for traverse grinding and somewhat after the loading position 27.

The arm 30, conveniently pivoted to a lug 32 of the stationary supporting structure, presents an upward bevel 33 toward the approaching work pieces, riding over their projecting ends with or without contact.

The work pieces that have been properly positioned in their respective holders pass under the arm 30 without lifting it to any material extent.

If however a work piece has not been properly inserted in its holder its lower end does not lie flush with a circumferential seat (not shown) provided for it in the holder. As a result the upper end of the piece projects abnormally and when the piece passes under the arm it raises the arm to a

greater extent than is the case when the piece is properly seated in its holder.

I use this abnormal movement of the arm 30, which takes place only in the event of an improper seating of the work piece to prevent the usual return of the carrier 16 to its position for traverse grinding.

I do this in any suitable way, in Figure 2 closing an electric circuit to electrically operate a latch 34 and in Figure 3 using the upward movement of the arm 30 to mechanically operate a latch 34', either latch being adapted to prevent the downward movement of the carrier.

Figure 2 the abnormal angular movement of the arm closes an electric circuit at 35 to energize an electric magnet 36 having an armature adapted to rock the latch member 34 into position for stopping the downward movement of the carrier.

The latch member is pivoted at 37 to a bracket 38 on the turntable and carries a lower hook 39 adapted to swing under a downwardly directed abutment 40 when the magnet is energized.

The carrier is normally supported and traversed by the rod 19 the bottom of this rod resting upon the surface of the traverse cam 18. When the bottom of the rod reaches the descending portion 41 of the traverse cam, the carrier normally then moves down into position for traverse grinding but if an abnormal condition at the unit has operated the latch, the carriers abutment 40 comes down upon the hook 39 which then supports the carrier, the bottom of the rod remaining somewhat above the upwardly presented surface of the cam.

The latch may be made operative under any number of different contingencies likely to produce abnormal conditions at the unit.

Of these different contingencies the most usual is that of an imperfect seating of a work piece in its holder and that of a wheel having gradually worn away to an extent that it is no longer effective to properly grind and in Figure 2, I show the same latch 34 operated if either one of these contingencies take place.

As the wheel gradually wears away the position of the wheel unit along its horizontal guideway is gradually changed, the wheel unit being fed inwardly along its guideway by the star wheel 22 which engages the feed pin 26.

After the wheel has been reduced in size to a predetermined limit contact members 42 and 43 respectively mounted upon the wheel unit and its carrier make contact, closing an electric circuit through the magnet 36 and operating the latch to prevent the return of the carrier to grinding position after the insertion of a work piece.

It will be noted that in the illustration

the individual electromagnets 36 are connected in parallel to a suitable battery 44. The other side of the battery is grounded at 45 and the other side of the magnet goes to ground through the contact members 35 when there has been an imperfect insertion of a work piece or through the contacts 42 and 43 if the wheel is worn away to its predetermined lower limit.

In the structure shown in Figure 3, I use mechanical means for operating the latch 34' and illustrate that the same or separate latches may be operated by the different abnormal conditions under which it is desired to prevent the return of the wheel unit to its grinding position.

The latch 34' comprises a bell crank rocker pivoted at 46 to a portion of the turntable and presenting an upwardly extending arm 47 to engage the carrier and a horizontal outwardly extending arm 48 to be engaged by the inner end of the arm 30.

The hub of the rocker is provided with adjacent V-notches 49 and 50 that alternatively receive the beveled end of a click member 51 spring-pressed into one or other of the notches.

The click member is normally in the lower notch and in this position the upwardly presented arm 47 is out of the way of the carrier permitting the carrier to move down to grinding position without striking.

The arm 30 is preferably angularly adjustable at 52 as to initial position, which is set so that the work pieces properly seated in their respective holders successively engage without materially raising the arm.

If a work piece is inserted imperfectly in its holder its top unduly projects upwardly, raising the arm 30 as it passes under which in turn angularly deflects the rocker bringing the upper notch 49 into position to receive the click member 51 which further deflects the rocker into a position at which the top of the vertical arm 47 is latched under a downward abutment 40' of the carrier, preventing the carrier from going down into position for traverse grinding.

In Figure 3 the carrier is provided with a horizontal bolt 53 provided with adjacent V-notches 54 and 55 that alternatively receive the beveled end of a click member 56 spring-pressed at 57 into one or other of the notches.

The point of the click is normally in the right-hand notch and the bolt 53 does not interfere with the return of the carrier, to position for traverse grinding.

If however a wheel wears away to the predetermined limit of reduction the outer end of the bolt is engaged by the inner end of a suitable pin 58 pushing the bolt inwardly until the click enters the outer notch when the bolt springs inwardly under the action of the click and latches under a suitable abutment 59 of the turn-table preventing the

carrier from moving down to position for traverse grinding.

In operation the work pieces are loaded into the successive holders at the point 27.

5 At this time the wheel units operating at the respective holders are up out of the way and I have provided means for maintaining any wheel unit safely away from its grinding position in the event that a disadvantageous abnormal condition be present at the unit.

10 Illustrated examples of disadvantageous abnormal conditions under which the wheel is maintained safely away from grinding position have been an imperfect seating of the work piece in its holder and the reduction in size of the wheel through use to a predetermined limit beyond which it is considered inadvisable to use the wheel for 15 grinding.

20 These two abnormal conditions are the most usual ones that make it undesirable to permit the grinding wheel to descend to grinding position, and while I have not illustrated the invention applied for operation in the presence of other disadvantageous abnormal conditions I contemplate doing so whenever such conditions arise.

25 In view of my invention and disclosure 30 variations and modifications to meet individual whim or particular need will doubtless become evident to others skilled in the art, to obtain all or part of the benefits of my invention without copying the structure 35 shown, and I, therefore, claim all such in so far as they fall within the reasonable spirit and scope of my invention.

Having thus described my invention, what 40 I claim as new and desire to secure by Letters Patent is:—

1. In a multiple grinder, a turn-table, 45 grinding units mounted on the turn-table spaced therearound, each unit comprising a revolving work-holder and a grinding wheel, supporting structure for the turn-table having unloading and loading points for the units adjacent one side of the table, and mechanism for moving the wheels successively away from the grinding position 50 before the unloading point is reached and back into grinding position after the loading point has been passed, in combination with a safety device for preventing the movement of a grinding wheel to its grinding 55 position preparatory to initially grinding the work and operative by means of an abnormal condition at the unit.

2. In a multiple grinder, a turn-table, 60 grinding units mounted on the turn-table spaced therearound, each unit comprising a revolving work-holder and a grinding wheel, supporting structure for the turn-table having unloading and loading points for the units adjacent one side of the table, and mechanism for moving the wheels suc-

cessively away from the grinding position before the unloading point is reached and back into grinding position after the loading point has been passed, in combination with a latch adapted to prevent a grinding wheel from moving back into its position for grinding, and means for operating the latch by an abnormal condition at the unit.

3. In a multiple grinder, a turn-table, grinding units mounted on the turn-table spaced therearound, each unit comprising a revolving work-holder and a grinding wheel, supporting structure for the turn-table having unloading and loading points for the units adjacent one side of the table, and mechanism for moving the wheels successively away from the grinding position before the unloading point is reached and back into grinding position after the loading point has been passed, in combination with mechanism adapted to prevent the movement of the wheel to its grinding position preparatory to initial grinding comprising a latch, connections between the latch and wheel adapting the latch to maintain the wheel in raised position, an electromagnet adapted to operate the latch, an electric circuit adapted to operate the magnet and contact means for closing the circuit operative preparatory to initial grinding and after loading by an abnormal condition of the unit.

4. In a multiple grinder, a turn-table, grinding units mounted on the turn-table spaced therearound, each unit comprising a revolving work-holder and a grinding wheel, supporting structure for the turn-table having unloading and loading points for the units adjacent one side of the table, and mechanism for moving the wheels successively away from the grinding position before the unloading point is reached and back into grinding position after the loading point has been passed, in combination with mechanism adapted to prevent the movement of the wheel to its grinding position comprising a latch, connections between the latch and wheel adapting the latch to maintain the wheel in raised position, an electromagnet adapted to operate the latch, an electric circuit adapted to operate the magnet, and contact means for closing the circuit operative by an abnormal extension of a work piece if the work piece is imperfectly seated in its holder and other contacts for closing the circuit operative by an inward extension of the wheel unit when the wheel is worn away to a predetermined limit.

5. In a multiple grinder, a turn-table, grinding units mounted on the turn-table spaced therearound, each unit comprising a revolving work-holder and a grinding wheel, supporting structure for the turn-table having unloading and loading points for the units adjacent one side of the table, mecha-

nism for moving the wheels successively away from the grinding position before the unloading point is reached and back into grinding position after the loading point has been passed, in combination with mechanism adapted to prevent the movement of the wheel to its grinding position including a latch to maintain the wheel in raised position, an electromagnet to operate the latch, an electric circuit, and contact means for closing the circuit operative by a work piece if the work piece is imperfectly seated in its holder and other contact means for closing the circuit operative by the wheel unit when the wheel unit reaches a predetermined position upon its carrier.

6. In a multiple grinder, a turn-table, grinding units mounted on the turn-table spaced therearound, each unit comprising a revolving work-holder and a grinding wheel, supporting structure for the turn-table having unloading and loading points for the units adjacent one side of the table, and mechanism for moving the wheels successively away from the grinding position before the unloading point is reached and moving it back into grinding position after the loading point has been passed, in combination with a click latch adapted to latch the carrier in raised position and means operative by an abnormal condition at the unit for operating the latch.

7. In a multiple grinder, a turn-table, grinding units mounted on the turn-table spaced therearound, each unit comprising a revolving work-holder and a grinding wheel, supporting structure for the turn-table having unloading and loading points for the units adjacent one side of the table, mechanism for moving the wheels successively away from the grinding position before the unloading point is reached and moving it back into grinding position after the loading point has been passed in combination with a click latch adapted to maintain the carrier in raised position, and means operated by the upper end of a work piece if the work piece has been imperfectly seated in its holder for operating the latch.

8. In a multiple grinder, a turn-table, grinding units mounted on the turn-table spaced therearound, each unit comprising a revolving work-holder and a grinding wheel, supporting structure for the turn-table having loading and unloading points for the units adjacent one side of the table, and mechanism for moving the wheels successively away from the grinding position before the unloading point is reached and back into grinding position after the loading point has been passed, in combination with a safety device adapted to prevent the return of a grinding wheel to its grinding position when the wheel has worn away to a predetermined limit.

9. In a multiple grinder, a turn-table, grinding units mounted on the turn-table spaced therearound, each unit comprising a revolving work-holder and a grinding wheel, supporting structure for the turn-table having loading and unloading points for the units adjacent one side of the table, and mechanism for moving the wheels successively away from the grinding position before the unloading point is reached and back into grinding position after the loading point has been passed, in combination with a latch adapted to prevent a grinding wheel from returning to its position for traverse grinding and mechanism operated by a work piece when the work piece has been imperfectly seated in its holder for operating the latch.
